FRED C. PARTELL, OF LEWISTON, MAINE

BLOTTER HOLDER

Application filed December 29, 1928. Serial No. 329,121.

This invention relates to blotter holders and more particularly to that type embodying a holder body having a longitudinally convex surface upon which a blotter is to be held, the body being provided with a handle whereby the device may be readily manipulated in applying the blotter to the surface to be blotted, and one of the objects of the present invention is to provide an extremely simple and inexpensive means for retaining and securing in place the ends of the blotter sheet so that the sheet will be held in snug contact with the convex surface of the blotter holder body.

Another object of the invention is to provide a blotter holder in which the retaining means for the ends of the blotter is devoid of any pivoted or other moving parts which would be liable to become disarranged, each retaining member being formed from a single strand of resilient wire and assembled with the body of the blotter holder by a simple arrangement insuring of a stable and secure connection of the member with the holder body.

While the accompanying drawings and the description which is to follow, constitute a disclosure of the preferred embodiment of the invention, it will be understood that various changes may be made within the scope of what is claimed.

In the accompanying drawings:

Figure 1 is a view in side elevation of the blotter holder embodying the invention, a blotter sheet being assembled therewith;

Figure 2 is an end elevation of the device with the blotter sheet in place thereon;

Figure 3 is a top plan view, a portion of the holder body being broken away and certain anchoring elements being shown in section;

Figure 4 is a bottom plan view of the holder and the blotting sheet thereon;

Figure 5 is a detail fragmentary vertical sectional view illustrating the manner in which the ends of the blotting sheet are anchored;

Figure 6 is a fragmentary bottom plan view of one end of the top member or cap section of the body of the holder.

The device embodying the invention comprises a body member 1 which is preferably of wood and which has a flat upper side indicated by the numeral 2 and has its under side, which is indicated by the numeral 3, convexly curved from end to end, the side faces of the body preferably occupying parallel vertical planes. The body of the device further comprises a top section 4 which is united to the flat upper side 2 of the body 1, preferably by adhesive, and which is provided, centrally, with an upstanding handle knob 5, the side and end edges of the member 4 being in registration with the corresponding margins of the upper surface 2 of the said body 1.

It will be observed by reference to Figures 1 and 5 of the drawings that the upper surface 2 and convex under surface 3 of the body member 1 merge substantially at a sharp end edge which is in registration with the respective end edge of the top section 4 of the body and the invention contemplates the provision, at each end of the body structure, of a resilient clip for anchoring and snugly holding a respective end of the blotting sheet, which is indicated by the numeral 6, and which is disposed, as most clearly shown in Figures 1 and 5 of the drawings, against the surface 3 of the body member 1 and this sheet is preferably of the same marginal dimensions as the under side 3 of the said body member so that it will be marginally in registration therewith. The retaining clips, referred to above, are each formed from a single length of resilient wire and each clip comprises a gripping portion which is to grip or engage the end of the blotting paper sheet 6 and which portion comprises a bight 8 and side portions 9 forming a substantially U-shaped loop which is of sufficient length to substantially engage the respective end of the blotter sheet 6. The side members 9 of the loop are formed with correspondingly located acute bends 10 to provide extensions 11 which are parallel to each other and which, at the time of assemblage of the parts of the device are disposed to rest flat against the upper side 2 of the body 1, and these side portions 11 have their rear end portions bent to extend laterally in opposite directions as indicated

by the numeral 12, and studs 13 are driven into the upper face 2 of the body 1 at spaced points so as to engage in the bends between the portions 11 and their end extensions 12 as most clearly shown in Figure 3 of the drawings, the member 7, as a whole, being in this manner securely anchored upon the respective end of the body 1 and with the end of said body and the end marginal portion of the blotter sheet 6 engaging between the loop comprising the portions 8 and 9, and the side members 11, so that the end margin of the blotting sheet will be securely held against the under face 3 of the body 1. In order that the portions 11 and 12 of the two anchoring or clip members 7 may be housed between the upper side 2 of the body 1 and the respective ends of the member 4, the member 4 is formed, in its under side, at each end, with a transverse recess 14 which extends substantially parallel to the adjacent end edge of the member 4 and which is provided with a branch 15, intermediate its ends, which branch opens through the said margin of the member. By reference to Figure 3, in which figure the recess 14 and its branch 15 are illustrated in dotted lines, it will be observed that the side members 11 of the clip engage in the branch 15 of the recess 14 and substantially against the side walls thereof so that the clip is braced against any lateral displacement, and it will also be evident, by reference to this figure and Figure 5 of the drawings, that the angularly turned end portions 12 of the side members 11 of the clip together with the studs 13, are housed within the recess 14.

From the foregoing description of the invention it will be evident that a blotter sheet of the proper dimensions may be readily disposed against the longitudinally convex under face 3 of the body member 1 of the holder and, by slightly springing the loop comprising the bight 8 and side portions 9, of the clips, outwardly, by engaging the finger nail beneath the bight of the respective clip loop, the corresponding end of the blotter sheet may be engaged between this portion of the clip and the longitudinally convex under face 3 of the body 1. The clip, as will be noted from the drawing and the foregoing description of the invention, is anchored in such a manner that it is not liable to become in any way displaced and, inasmuch as it does not embody any movable part, there is no likelihood of disengagement of the end of the blotting sheet from either clip and therefore the sheet is securely retained in place snugly extending over the under surface 3 of the body member 1 of the holder.

Having thus described the invention, what I claim is:

1. A blotter holder comprising a body member having its under side convexly curved from end to end, studs upon the upper side of the body member, and resilient clips at the

ends of the body member each including spaced side portions and laterally directed ends engaging the studs at the respective end of the body member and a loop including side members constituting angularly directed extensions of the first mentioned side portions, and a connecting bight, the side portions and bight of the loop bearing yieldably against the said under side of the body member at the ends thereof and constituting means for holding the ends of a blotter sheet when such sheet is disposed in surface contact with the said under side of the body.

2. A blotter holder comprising a body member having its under side convexly curved from end to end, studs upon the upper side of the body member, resilient clips at the ends of the body member each including spaced side portions and laterally directed ends engaging the studs at the respective end of the body member and a loop including side members constituting angularly directed extensions of the first mentioned side portions, and a connecting bight, the side portions and bight of the loop bearing yieldably against the said under side of the body member at the ends thereof and constituting means for holding the ends of a blotter sheet when such sheet is disposed in surface contact with the said under side of the body, and a top member secured to the upper side of the body member and having recesses in its contacting face accommodating the clip side portions and their laterally directed ends and also the said studs.

In testimony whereof I affix my signature.
FRED C. PARTELL.
